EQUIPMENT RACK

Raymond O. Miller, United States Army

Application August 21, 1942, Serial No. 455,585

3 Claims. (Cl. 211—86)

(Granted under the act of March 3, 1883, as
amended April 30, 1928; 370 O. G. 757)

The invention described herein may be manufactured and used by or for the Government for governmental purposes, without payment to me of any royalty thereon.

This invention relates to equipment racks and more particularly to an equipment rack having its principal components formed into an integral unit, attachable to a suitable supporting member by means of a single attaching plate and a pair of fastening elements.

It is an object of this invention to provide an equipment rack which will combine maximum strength with simplicity of construction whereby a device may be produced which will withstand the rigors of military usage.

It is a further object of this invention to provide a device of the character described which will be easy to install and require a minimum number of separable elements whereby the likelihood of lost parts is eliminated.

These and other objects and advantages of this invention will become apparent upon a consideration of the following detailed description, when taken in conjunction with the accompanying drawing, in which:

Fig. 1 is a top view of an embodiment of the invention shown attached to a suitable support;

Fig. 2 is a side elevation of the device;

Fig. 3 is a rear elevation of the device; and

Fig. 4 is a perspective view of the device in its attached position.

Referring to Figs. 1 and 2, it will be seen that the main supporting elements consist of bars 10 and 12. The bar 10 is cut off at an angle and is rigidly attached to the supporting plate 14 by means of weld 16. I prefer to form the supporting plate 14 of a section of angle iron. The bar 12 is also cut off at an angle and is rigidly attached to the guide member 18 by means of weld 20. I prefer to make the guide member 18 from a single sheet, bent so as to form the shelf 19, the face 26 and side arms 28 and 30, although it is clear that the face and arms may be shaped from a single piece of strap metal and the shelf 19 welded thereto.

In order properly to space the supporting bars 10 and 12, there is provided the spacing bar 22 welded at its lower end to the bar 12 and at its upper end to the lower face of the supporting plate 14.

It will be seen that the assembly just described provides an integral unit which is simple to construct and yet, due to the supporting plate 14, the shelf 19 and the spacing member 22, will offer a maximum resistance to torsional strains.

In order to provide for the easy attachment of my device to a suitable supporting member, I prefer to use the construction as more clearly shown in Figs. 1 and 3. It will be seen that the

5 supporting plate 14 has its vertical face of sufficient width to extend over either side of the supporting member 31. In each overhanging portion there is provided a hole adapted to receive the attaching elements 32 and 34. The attaching elements 32 and 34 are provided with a threaded portion adapted to engage the nuts 33 and 35 respectively. A back plate 36, similar to the supporting plate 14 is arranged to receive the attaching members 32 and 34.

10 To set up my device, the unit is placed in position, the back plate 36 placed over the attaching members 32 and 34, and the nuts 33 and 35 are tightened, drawing the plates 14 and 36 tightly about the supporting member 31 as is shown in

15 Fig. 4. If desired, the back plate 36 may be provided with lateral slots arranged to engage the ends of the attaching members 32 and 34 and the threaded portion of the attaching member bruised whereby the nuts 33 and 35 cannot be removed. This latter construction provides an arrangement whereby the possibility of the loss 20 of a part of the device is greatly reduced. It is clear that one slot and one hole may be provided in the back plate 36 whereby the elements of the device will always remain together, the plate 36 merely being rotated 180° when it is desired to remove or attach the device to a supporting member.

25 While I have described my invention with particularity, it is to be understood that I do not wish to be limited to the particular details and arrangements illustrated since various modifications within the spirit of the invention will suggest themselves to those skilled in the art.

30 Having thus described my invention, what I claim as new and wish to protect by Letters Patent is:

35 1. A unitary equipment rack adapted to be attached to an upright support, comprising upper and lower equipment supporting members, means rigidly spacing said supporting members, a substantially U-shaped member attached near said lower supporting member, said U-shaped member arranged to partially encircle said support, means attached near said upper supporting member arranged to encircle said support, and means to tighten said encircling means about said support.

40 2. A unitary equipment rack adapted to be attached to an upright support, comprising upper

and lower equipment supporting members, means rigidly spacing said supporting members, a substantially U-shaped member attached near said lower supporting member, said U-shaped member arranged to partially encircle said support, means attached near said upper supporting member arranged to encircle said support, and means to tighten said encircling means about said support, said encircling means comprising front and rear plates having openings therein arranged to receive tensionable members.

3. A unitary equipment rack adapted to be attached to an upright support, comprising upper and lower equipment supporting members, a substantially U-shaped member rigidly attached near said lower supporting member, said U-shaped member being arranged to partially surround said support, a front attaching plate rigid-

ly attached to said upper supporting member, said front attaching plate having openings in each end thereof arranged to receive suitable securing members, said openings being spaced a distance somewhat greater than the width of said support, a spacing bar rigidly attached between said upper and lower supporting members, securing members engaged in said front attaching plate openings, said securing members having a length somewhat greater than the thickness of said support, a rear attaching plate provided with openings arranged to engage said securing members, and means cooperating with said securing members whereby said front and rear attaching plates may be tightened about said support.

RAYMOND O. MILLER.
